CLAIM

The ornamental design for a versatile pull toy, as shown.

DESCRIPTION

FIG. 1 is a perspective view of the versatile pull toy design of the invention as viewed from the front, top and right side;

FIG. 2 is a top plan view of the device of FIG. 1;

FIG. 3 is a front elevation of the device of FIG. 1;

FIG. 4 is a right side elevation of the device of FIG. 1;

FIG. 5 is a rear elevation of the device of FIG. 1;

FIG. 6 is a left side elevation of the device of FIG. 1;

FIG. 7 is a bottom plan of the device of FIG. 1;

FIG. 8 is a top plan of the device of FIG. 1 showing it in a flexed condition;

FIG. 9 is a perspective view of a first alternate embodiment of a versatile pull toy; and,

FIG. 10 is a top plan view of yet another embodiment of the versatile pull toy, of the invention.

*FIG. 8.**FIG. 9.**FIG. 10.*
